DEVICE FOR CONTROLLING AGENTS OF COMBUSTION

Carl Otto, Essen-Ruhr, Germany

Application December 11, 1926, Serial No. 154,209
In Germany December 16, 1925

11 Claims. (Cl. 277—6)

This invention relates to a device for controlling the supply and discharge of the agents of combustion in regenerative furnaces.

In all kinds of regenerative furnaces, such as coke ovens and the like, means must be provided to control the supply of the agents of combustion to be preheated, such as gas and air, in the regenerator and to discharge the hot waste gases, which heat the regenerator. These means must permit the change of the direction of flow of the agents passing through the regenerator, upon reversal of the furnace. At the same time these must prevent any transition or leakage from the conduits of the agents of combustion to be preheated, that is air, or air and gas, to the conduits which carry off the waste heat.

My invention has for its object to provide a particularly simple and efficient embodiment of a controlling device of this type, in which the requirements pointed out above, are met in the most satisfying manner.

In order to allow my invention to be more easily understood, an example of the same, adapted to be used with coke ovens, heated with strong or weak gas, i. e. heated with coke oven gas or with producer or blast furnace gas, will be described in detail with reference to the drawing which forms part of this specification. In this drawing:

30 Figure 1 is a vertical longitudinal section through the controlling device.

Figure 2 is a horizontal section on line 2—2 of Figure 1, and

Figure 3 is a detail view on an enlarged scale.

35 The controlling device consists of a double seat valve, the stationary parts of which are a lower valve chamber *a* and an upper valve chamber *b*, which is constructed in the usual way as a hollow cylinder having a flanged pipe coupling *b*¹ integral with it. The movable parts of the device substantially consist of a lower valve *c* and an upper valve *d*, which are mounted on a common stem *e*. Lower valve *c*, which preferably has guide vanes *c*¹, is adapted to shut off the chamber *a*, from the lower flanged pipe coupling *a*¹, while the upper valve *d*, shuts it off from chamber *b*. The double valve is constructed as a gravity valve, without any spring load. Upon lifting stem *e*, the valves *c* and *d*, move upward, 45 as they are jointly lifted from their seats *a*² and *b*², respectively, by collars *f*, *g*, fast on stem *e* and engaging the valves from below. When stem *e* is lowered, the valves *c* and *d*, come to rest upon their seats again by the action of their 50 own weight.

The upper valve *d*, has screwed in it a tube *h* (Fig. 3), surrounding the valve stem *e*, with clearance, and, likewise, capable of being shifted relatively to the chambers *a* and *b*. On the chamber *b*, the tube *h* is tightened by a stuffing box *i*. 60 This arrangement makes it possible to actuate the upper valve *d*, independently of the lower valve *c*, by means of an actuating lever (not shown), attached to the tube *h*, or to actuate both valves simultaneously by means of the stem *e*. A locking lever *k*, Fig. 1, may engage the tube *h*, as shown, to hold the valve *d*, in its open position.

The coupling *a*¹, of chamber *a*, has connected to it a waste heat conduit *m* of the furnace. 70 Chamber *a*, is also provided with two lateral flanged couplings *a*³, to which are connected channels *n*, *n*¹, which lead to the air regenerator (not shown). Chamber *a*, which may also communicate with chamber *b*, by means of valve *d*, 75 is also in communication with the outer air by means of an opening at *a*⁴, which may be closed by flap *o*. Pipe *p*, connected to coupling *b*, of chamber *b*, leads to a gas regenerator (not shown) and is provided with a coupling *p*¹, which 80 is in communication with the weak gas main by means of gas supply conduit *p*². When the oven is heated with strong gas, i. e. coke oven gas and pipes *p* and *n*, *n*¹, are all supplied with air, in order 85 to insure a uniform distribution of the air entering through opening *a*⁴, a baffle plate *q* may be arranged on the flange of the opening *a*⁴, as illustrated in Figure 1.

The adjustment of the controlling device to fulfill the different conditions of operation takes 90 place in the following manner.

When one controlling device is positioned so as to supply to the regenerators, another valve is so positioned as to discharge the waste gases coming from the furnace to a waste heat conduit.

When the coke oven is to be heated by weak gas, the communication between the coupling *p*¹, to the weak gas main is established by opening valve *p*³ in pipe *p*², and the flap *o* of opening *a*⁴, is opened so as to supply air to chamber *a*. 100 The valves *c* and *d* are in closed position. Weak gas flows from the main through coupling *p*¹ and pipe *p*, to the gas regenerator (not shown). The air for combustion enters through opening *a*⁴, into the chamber *a* and passes through couplings *a*³ and twin channels *n*, *n*¹ to the air regenerators (not shown). After reversal pipe *p*, is shut off from the weak gas main by closing valve *p*³ so that there is no further flow of weak gas from the main through pipe *p*. The flap *o*, is 110

also closed, so that there is no further flow of air through chamber *a*, to the channels *n*, *n*¹. The valves *c* and *d*, are opened by lifting stem *e*. Waste heat coming from the regenerators, which 5 previously operated as inflow regenerators, now flows through the pipe *p* and channels *n*, *n*¹, into the chambers *b* and *a*, and passes through the bottom coupling *a*¹ to waste heat channel *m*.

When the coke oven is to be heated by strong 10 gas, i. e. coke oven gas, all the regenerators are supplied with air to be preheated. The coupling *p*¹, by means of valve *p*³, remains shut off from the weak gas main, flap *o*, is opened and the upper valve *d*, is opened by lifting tube *h*, and fixed 15 in open position by locking lever *k*. Air for combustion enters through opening *a*⁴ and passes through chambers *a* and *b* to pipe *p* and channels *n*, *n*¹, and from them to the regenerators (not shown). After reversal the same adjustments 20 are made as with weak gas heating, viz. flap *o*, is closed, pipe *p*¹, remains shut off from the weak gas main and valves *c* and *d*, are opened. The waste gases flow, as before, through pipe *p* and channels *n*, *n*¹, through the chambers *b* and 25 *a*, into the waste heat channel *m*.

In addition to the advantages given in the above described operation, my controlling device results in the advantage that when the regenerative furnace is thrown out of operation with the 30 valves *d* and *c*, closed, the gas main, is shut off from the waste heat channel by two closed valves, so that any passage of gas to the waste heat channel is prevented with the greatest security. The same is the case when the furnace is operated 35 with weak gas. Weak gas from the main entering pipe *p*, is shut off from the waste heat channel by both valves *d* and *c*, which are closed. During heating with strong gas, (coke oven gas), valve *d*, is open so that pipe *p* may also be supplied 40 with air, but valve *p*³ is closed and this with the entering air flowing through pipe *p* and channels *n*, *n*¹, forms a closure preventing the leakage of weak gas to the waste heat channel *m*.

The present invention, it will be seen, offers a 45 simple controlling device which is reliable in operation and may be applied to all types of regenerative furnaces.

What I claim as new and desire to secure by Letters Patent, is:—

50 1. A device for controlling the flow of gases to and from regenerators comprising in combination, two communicating chambers, one having an air inlet port, a valve for the port, a conduit communicating with and adapted to connect each of the said two chambers with a separate regenerator, a waste heat conduit connected with one of said chambers, and a pair of valves, one adapted to control communication between the said two chambers and the other adapted to control communication with the waste heat conduit.

55 2. A device for controlling the flow of gases to and from regenerators comprising in combination, a pair of chambers, arranged one above the other, the lower chamber having an air inlet port, a valve for the port, a conduit communicating with and adapted to connect each chamber with a separate regenerator, a waste heat conduit connected with the lower chamber, and a pair of coaxially arranged valves, one adapted to control communication between the chambers and the other to control communication with the waste heat conduit.

60 3. A device for controlling the flow of gases to and from regenerators comprising in combination,

a pair of chambers arranged one above the other, the lower chamber having an air inlet port, a valve for the port, a conduit communicating with and adapted to connect each chamber with a separate regenerator, a waste heat conduit connected with the lower chamber, and a pair of coaxially arranged gravity valves, one adapted to control communication between the chambers and the other to control communication with the waste heat conduit.

65 4. A device for controlling the flow of gases to and from regenerators comprising in combination, two communicating chambers, one having an air inlet port, a valve for the port, a conduit communicating with and adapted to connect each of the said two chambers with a separate regenerator, a waste heat conduit connected with one of said chambers, a pair of coaxially arranged valves, one adapted to control communication between the said two chambers and the other to control communication with the waste heat conduit, and means for jointly operating said pair of valves.

70 5. A device for controlling the flow of gases to and from regenerators, comprising in combination, a pair of chambers arranged one above the other, the lower chamber having an inlet port, a valve for the port, a conduit communicating with and adapted to connect each chamber with a separate regenerator, a waste heat conduit connected with the lower chamber, a pair of valves arranged coaxially, one above the other, on a common stem, means for operating said valves jointly, and a tube surrounding said stem and secured to the upper valve, whereby it can be 75 separately operated.

75 6. A device for controlling the flow of gases to and from regenerators comprising in combination, a pair of chambers, arranged one above the other, the lower chamber having an air inlet port, a valve for the port, a conduit communicating with and adapted to connect each chamber with a separate regenerator, a waste heat conduit connected with the lower chamber, a pair of valves arranged coaxially, one above the other, on a common stem, means for jointly operating 80 said pair of valves, a tube surrounding said stem and secured to the upper valve, and adapted to separately lift said valve, and means for locking the upper valve in lifted position.

80 7. A device for controlling the flow of gases to and from regenerators comprising in combination, a pair of chambers, one above the other, the lower chamber having an air inlet port, a valve for the port, an upwardly and inwardly extending baffle plate mounted in the lower chamber adjacent said port, a conduit communicating with and adapted to connect each chamber with a separate regenerator, a waste heat conduit connected with the lower chamber, and a pair of valves arranged 85 coaxially one above the other, one adapted to control communication between the chambers, and the other to control communication with the waste heat conduit.

85 8. A device for controlling the flow of gases to and from regenerators, comprising in combination, a pair of chambers, one above the other, the lower chamber having an air port, a valve for the port, an inwardly and upwardly extending baffle plate mounted in the lower chamber adjacent said port, a conduit connecting each chamber with a separate regenerator, a waste heat conduit connected with the lower chamber, a pair of valves arranged coaxially, one above the other, on a common stem, one adapted to control communication with the waste heat conduit.

cation between the chambers and the other to control communication with the waste heat conduit, means for operating said pair of valves jointly, and means for separately operating the 5 upper valve.

9. A device for controlling the flow of gases to and from regenerators, comprising in combination, a pair of chambers, one having an inlet port, a valve for the port, a conduit communicating 10 with and adapted to connect each chamber with a separate regenerator, a pipe communicating with one of said conduits and adapted to supply fuel gas thereto, a valve for said pipe, a waste heat conduit connected with one of said chambers, and a pair of coaxially arranged valves, one 15 adapted to control communication between the chambers and the other to control communication with the waste heat conduit.

10. A device for controlling the flow of gases to and from regenerators, comprising in combination, a pair of chambers, one above the other, the lower chamber having an air inlet port, a valve for the port, a conduit communicating with and adapted to connect each chamber with a separate 20 regenerator, a pipe communicating with the con-

duit of the upper chamber, and adapted to supply fuel gas to said conduit, a valve for the pipe, a waste heat conduit connected with the lower chamber, and a pair of valves arranged coaxially one above the other, one being adapted to control communication between the chambers and the other valve being adapted to control communication with the waste heat conduit.

11. A device for controlling the flow of gases to and from regenerators, comprising in combination, a pair of chambers, one above the other, the lower chamber having an air port, a valve for the port, a conduit communicating with and adapted to connect each chamber with a separate regenerator, a pipe communicating with the upper conduit, and adapted to supply fuel gas thereto, a valve for the pipe, a waste heat conduit connected with the lower chamber, a pair of valves arranged coaxially, one above the other, one valve being adapted to control communication between the chambers and the other to control communication with the waste heat conduit, means for operating the pair of valves jointly and means for separately operating the upper valve.
